PATENTED APR. 23, 1907.

C. H. HAESELER.
PNEUMATIC TOOL.
APPLICATION FILED FEB. 21, 1907.

UNITED STATES PATENT OFFICE.

CHARLES H. HAESELER; OF NEW YORK, N. Y., ASSIGNOR TO INGERSOLL-RAND COMPANY, A CORPORATION OF NEW JERSEY

PNEUMATIC TOOL.

No. 851,624.

Specification of Letters Patent.

Patented April 28, 1907

Application filed February 21, 1907. Serial No. 358,605.

To all whom it may concern:

Be it known that I, CHARLES H. HAESELER, of New York city, in the county of New York, and in the State of New York, have invented a certain new and useful Improvement in Pneumatic Tools; and I do hereby declare that the following is a full, clear, and exact description thereof, reference being had to the accompanying drawings, in which—

Figures 1 and 2 are longitudinal, sectional views of a pneumatic tool embodying my invention, the parts being shown in different positions; and Figs. 3 and 4 are respectively a side elevation, and a longitudinal, sectional view of the valve-box and ring, showing the sealing devices.

The object of my invention has been to provide a pneumatic tool in which the construction shall be exceedingly simple; in which the air passages shall be few and direct, so that they may be easily formed and cleaned; in which the valve shall have a positive and certain action; in which the valve shall have but one wearing surface, so that it may be accurately fitted in the valve-chamber; and so that the wear shall be uniform and shall all take place upon a single surface and thus it may be easily compensated for; in which the valve shall move transversely to the length of the tool-casing, and shall be of relatively small diameter, whereby the length of the tool-casing may be relatively short; in which the valve shall be capable of being made of a length considerably greater than its diameter, whereby all tendency of the valve to cramp and stick may be avoided; and in which access to the valve can be sealed so as to prevent unauthorized interference with the valve; and to such ends my invention consists in the pneumatic tool hereinafter specified.

In the accompanying drawings I have illustrated what I consider to be the best embodiment of my invention, but such embodiment is only chosen for illustration, and it is to be understood that the invention is capable of embodiment in other forms.

In the embodiment shown in the drawings, my invention is shown as applied to a hammer, although the invention is applicable to any tool having a piston.

In the drawings the chipping-tool A is shown as seated in a block B having a bore adapted to receive the tool, the tool and bore

being of polygonal form to prevent the tool from turning. The block B is mounted in the end of a preferably cylindrical casing C, in which is formed a bore D, having in it a hammer in the form of a piston E. The end 60 of the bore opposite the tool is closed by a cylindrical valve-box F that is held in place over the bore by a cap G, the latter having a recess to receive the valve-box, and being screwed onto the casing by a thread H. 65 Dowel pins insure the proper location of the valve-box on the cylinder, so that the portions of the ports which are formed partly in the valve-box and partly in the cylinder will come into proper alignment. The cap is 70 provided with the usual handle having a connection for the hose, and with a valve for controlling the passage of air from the hose into the hammer. The air enters by a passage I into a chamber K and passes by a port 75 L into the valve-chamber M. The valve-chamber consists of the simple cylindrical bore passing through the valve-box from side to side, the ends of the chamber being closed by a ring N that is fitted over the 80 valve-box.

In order to insure that the various holes which it is necessary to make through the ring to permit exhaust from the ports in the valve-box shall always align with the said 85 ports, a pin f is secured in the valve-box, and a slot n is formed in the ring to engage the said pin. The valve O consists of a cylindrical body having two necks or grooves o and o' respectively formed therein, which are 90 to act like the under side of a D-valve. The air from the port L is transmitted either to the upper or lower end of the hammer-bore, according as the groove o is in communication with the port L as in Fig. 1, or the groove 95 o' as in Fig. 2. When the groove o is in communication with the port L, as in Fig. 1, the live air from the port L passes through a series of ports P into a port P' extending down the wall of the casing and ending in a port P² 100 that opens into the hammer-bore below the lower limit of the travel of the hammer. The live air reaches the upper end of the hammer-bore through a port Q which communicates with the port L through the groove o' when 105 the valve is in the position of Fig. 2. The exhaust from the lower end of the cylinder is through the ports P², P' and P, and by way of the groove o out through ports R which extend from the valve-bore through the valve- 110

box into an annular passage S surrounding the valve box, and thence through a bore T to the atmosphere. The exhaust from the upper end of the cylinder is by the port Q 5 through the groove o' and through ports U opening from the valve-bore through the valve-box and into the passage S, and thence to the atmosphere through the port T.

The valve has a constant pressure upon one end by the passage of live air through a very small port V from the recess K into one end of the valve-bore, the pressure being reduced below the normal live air pressure by the provision of a port W, which is somewhat 15 larger than the port V and which affords communication with the exhaust space S. The air entering the port V thus produces a constant but reduced pressure upon the adjacent end of the valve. The opposite end 20 X of the valve-bore communicates by ports Y, Y' and Y² with the hammer-bore at a point where a groove or neck E' in the hammer is in line with the bore when the hammer is at the lower end of its stroke. In this 25 position the said groove admits the live air from the recess K through a port Z in the wall of the casing, which port communicates with the port Z' that opens into the cylinder-bore at the level of the port Y². Thus, when 30 the groove E' is in proper position, live air passes from the recess K through the groove E' and by the ports Y², Y' and Y to the end X of the valve-bore, and produces pressure 35 on the adjacent end of the valve at the normal pressure of the air in the hose, and as this pressure is greater than the pressure permitted by the port W, the valve will be forced to the opposite end of its chamber. The 40 hammer is long enough so that the ports Z' and Y² are not uncovered by the hammer on its backward stroke. The port Y passes downward into the casing beyond the port Y² to a port Y³ opening into the lower end of the piston-bore, the port Y³ being opposite 45 an exhaust port A', with which it can communicate when the hammer has begun to travel backward on its return stroke.

In the operation of my pneumatic tool, the parts being in the position illustrated in Fig. 50 2, the live air entering the passage I passes through the port V and at a reduced pressure maintains the valve in the position of Fig. 2. In this position the air passes through the port L and by way of the groove o' to the port Q and drives the hammer down. The 55 air ahead of the hammer exhausts through the port A' and through the ports P², P' and P, passing through the groove o and out through the exhaust ports R. When the 60 hammer has reached a position in which the groove E' affords communication between the ports Z' and Y², the live air passes to the end X of the valve-bore, and, producing a pressure superior to the reduced pressure of 65 the opposite end of the bore, moves the valve

to the position of Fig. 1. In this position of the valve, the live air from the port L passes by the groove o to the ports P, P' and P² and, acting on the lower end of the hammer, forces it back. During this movement the air above the hammer exhausts by the port Q and groove o' through the exhaust port U, annular recess S, and exhaust port T. When the hammer has returned enough to uncover the ports Y³ and A', the air from the space X 70 exhausts by the ports Y', Y² and Y³ through the port A' to the atmosphere, permitting the reduced pressure from the port V to again return the valve to the position of Fig. 2. The parts have now been restored to the position of Fig. 2, and the cycle is repeated. 75

In order that the valves of pneumatic tools may work easily and at the same time prevent all possible leakage of air, it is necessary that they and the parts connected therewith be made with a very high standard of workmanship. The valves are, therefore, peculiarly liable to injury when access is obtained to them by workmen not specially trained in caring for them, and yet, owing to the presence of dirt, rust or gummed oil, or owing to their wear, it is occasionally necessary to get at them. It is desirable to have only specially trained workmen care for such valves, and in order to insure that those not authorized shall not interfere with the valves, I have devised the seal which I am about to describe. 90

A hole A² is bored through the ring N that fits around the valve-box and into the body of the valve-box; and a plug B² of some soft material is inserted in said hole. The material which I prefer to use is celluloid of some peculiar color, such as tortoise-shell. An unauthorized person is less likely to be able 100 to duplicate a peculiar color of celluloid than a common color, such as white. As a further precaution, the exposed end of the plug B² is impressed with some die, as with the letters I—R shown, so that any mutilation 105 will at once be apparent. As a further precaution the hole A² through the ring N is made larger than the hole in the valve-box, so that if the ring N were driven off, the portion of the plug B² which would be sheared off, would immediately fall into the exhaust space, because, the hole A², being larger than the plug, would not support such sheared off portion. To prevent the entire plug B² 115 from working out into the space S, a hole C² is bored from a face of the valve-box (preferably the under face) to intersect with the hole A², and a plug D² is driven into said hole and through a hole in the plug B², thus locking the larger plug in place. The plug B² 120 could shake out into the passage S surrounding the ring N, which passage is used for exhaust purposes, if it were not for the plug D². The latter plug has no opportunity to escape, because in the assembled position of the 125 130

parts, the hole O^2 is covered by the cylinder, against which it abuts.

When the tool is brought to a person authorized to take the valve-box apart, it can be readily told whether the box has been taken apart by an unauthorized person, because of any one of three evidences: The end of the plug B^2 will show mutilation; or it will have dropped into the exhaust space, because it has been sheared off by driving off the ring N ; or a plug of different material will have replaced the sealing-plug. When an authorized person desires to get at the valve, it is only necessary to run a drill into each of the holes A^2 and C^2 to immediately remove the plugs, and this is accomplished without injury to the valve-box, or the ring N , because the drills will follow the soft material of the plug.

It will be observed that the above described pneumatic tool has, among others, the following advantages: The air passages are few and direct, and they are, therefore, readily formed and easily kept clean. The differential pressures cause the valve to have a positive and certain action. The valve has but one wearing surface, and that surface being cylindrical, it is easy to accurately fit the valve to its bore, and as the wear all takes place upon this single surface, either a new valve or a new valve-box can be readily supplied to fit the worn part. The valve has its movement transversely to the length of the hammer cylinder, and, therefore, the box adds only its smallest dimension to the length of the cylinder, and the total length of the tool is much shorter than would be the case if the length of the valve were in line with the length of the cylinder. The valve is of small diameter compared with its length, and, therefore, the thickness of the valve-box in the direction of the length of the cylinder is relatively small, and the valve has a long guiding surface, and therefore has no tendency to cramp or stick in its bore. The unauthorized taking apart of the parts inclosing the valve will be prevented, because of the certainty of detection if this should be attempted.

By the term "soft" as applied to the material of the plug B^2 , is meant such material that it will not injure the ring or the valve-box if the plug B^2 is sheared off by driving the ring off the valve-box, and such material that it can be drilled out easily without causing the drill to cut into the material of the valve-box. Within these limitations, any special material can be used.

While I have described what I consider to be the best embodiment of my invention, I desire it to be understood that the principles can be embodied in different forms, and I desire not to be limited beyond the requirements of the prior art, and the terms of my claims.

Having thus described my invention, I claim—

1. In a pneumatic tool, the combination of a cylinder, a piston therein, a valve and valve-bore for controlling the supply and exhaust of air from said cylinder, said valve consisting of a solid cylindrical plug having peripheral grooves in its surface and having a single cylindrical wearing surface, and means for applying a reduced but constant pressure to one end of the valve, and an intermittent higher pressure to the other end thereof, for actuating the valve.

2. In a pneumatic tool, the combination of a cylinder and piston, a removable valve box, a valve contained in said box, a part removable with said box and which part must be moved relative to said box in order to obtain access to said valve, and means for sealing said part in position.

3. In a pneumatic tool, the combination of a cylinder and piston, a valve for controlling ports of said cylinder, a part which must be removed to obtain access to said valve, and a seal for said part, said seal being so constructed as to be substantially confined within the normal outlines of the parts.

4. In a pneumatic tool, the combination of a cylinder and piston, a valve for controlling ports of said cylinder, a part which must be removed to obtain access to said valve, and a seal for said part, said seal being composed of special material, whereby the seal cannot be easily replaced and simplicity of construction is rendered practicable.

5. In a pneumatic tool, the combination of a cylinder, a piston, a valve, and a part which must be removed to obtain access to said valve, a portion of said part being cut-away to register with a cut-away portion in the piece against which said part is seated, and a sealing piece occupying said cut-away portions and so constructed that it cannot be removed without mutilation.

6. In a pneumatic tool, the combination of a cylinder, a piston, a valve-box containing a valve-bore and a valve therein, a part which must be removed to obtain access to said valve, there being alining holes through said part and into said box, and a plug of special, soft material inserted in said holes.

7. In a pneumatic tool, the combination of a cylinder, a piston, a valve-box containing a valve-bore and a valve therein, a part which must be removed to obtain access to said valve, there being alining holes through said part and into said box, and a plug of special, soft material inserted in said holes, the exposed end of said plug having a design thereon to prevent mutilation.

8. In a pneumatic hammer, the combination of a cylinder, a piston-hammer therein, a cylindrical valve-box seated on the upper end of said cylinder, said valve-box having a bore formed therein, a valve mounted in aid

bore, a ring surrounding said valve-box, alining holes formed through said ring and said valve-box, and a plug of special, soft material inserted in said holes.

9. In a pneumatic hammer, the combination of a cylinder, a piston-hammer therein, a cylindrical valve-box seated on the upper end of said cylinder, said valve-box having a bore formed therein, a valve mounted in said bore, a ring surrounding said valve-box, alining holes formed through said ring and said valve-box, and a plug of special, soft material inserted in said holes, an exhaust space being formed around said ring, a hole being formed in the upper surface of said valve-box and intersecting said first mentioned hole, a second plug of soft material inserted in said last mentioned hole, and a handle secured on the upper end of the tool and covering the exposed end of said second plug.

10. In a pneumatic hammer, the combination of a cylinder, a piston-hammer therein, a cylindrical valve-box seated on the upper end of said cylinder, said valve-box having a bore formed therein, a valve mounted in said bore, a ring surrounding said valve-box, alining holes formed through said ring and said valve-box, and a plug of special, soft material inserted in said holes, the exposed end of said plug having a design thereon to prevent mutilation, an exhaust space being formed around said ring, a hole being formed in the upper surface of said valve-box and intersecting said first mentioned hole, a second plug of soft material inserted in said last mentioned hole, and a handle secured on the

upper end of the tool and covering the exposed end of said second plug.

11. In a pneumatic hammer, the combination of a cylinder, a piston-hammer mounted therein, a valve-box at one end of the cylinder, a cylindrical valve mounted in a bore formed in said box transverse to the axis of the cylinder, said valve consisting of a relatively long, solid cylindrical body having two annular grooves formed therein, a supply port in the upper part of said valve-box, ports opening from the valve-bore respectively into the upper and lower ends of the cylinder, a live air and an exhaust port communicating with one end of the valve-bore, the exhaust port being larger than the supply port, whereby a constant but reduced pressure is maintained at such end of the valve-bore, and supply and exhaust ports communicating with the opposite end of the valve-bore, said last mentioned ports being governed by the position of the piston-hammer, so that live air is alternately admitted and exhausted from said end of the valve-bore, and said grooves in said valve-body are alternately placed in position to connect said port in the top of said valve-box alternately with the ports communicating with the opposite ends of the cylinder.

In testimony that I claim the foregoing I have hereunto set my hand.

CHARLES H. HAESELER.
